UNITED STATES PATENT OFFICE.

FRANK H. PATRICK, OF NORWICH, CONNECTICUT.

MEANS FOR SUPPLYING OXYGEN TO FURNACES.

SPECIFICATION forming part of Letters Patent No. 760,804, dated May 24, 1904.

Application filed April 21, 1903. Serial No. 153,705. (No model.)

To all whom it may concern:

Be it known that I, FRANK H. PATRICK, a citizen of the United States, residing at Norwich, in the county of New London and State of Connecticut, have invented a new and useful Improvement in Means for Supplying Oxygen to Furnaces, of which the following is a specification.

The chief aim of my present invention is to provide, in connection with furnaces, means for introducing into the fire-pot or combustion-chamber, or both, a plentiful supply of fresh oxygen, whereby more perfect combustion of the coals and gases is assured than is possible in furnaces as now most commonly constructed—that is to say, in furnaces in which the supply of oxygen is passed upward from the ash-pit through the grate-bars. Incidentally I have also provided means for regulating said supply of oxygen and for protecting the openings through which the same passes into the furnace.

In order to explain my said improvements most clearly, I have provided the accompanying sheet of drawings, in which—

Figure 1 is a front side elevation of a steam-generator for house-heating purposes embodying said improvements, a portion of the fire-pot section being broken away to disclose the holes through which the oxygen is introduced, and also shows two of the shields provided to prevent ashes and coals from entering said holes. Fig. 2 is a cross-sectional view of said fire-pot section taken on the line 2 2 of Fig. 1, and Fig. 3 is a similar view taken on the line 3 3 of Fig. 1.

Referring to the said drawings, the letter *a* indicates the fire-pot section, the same being formed of two concentric cylindrical shells, whereby a water-jacket *a'* is provided that surrounds the combustion-chamber. At stated points in the said fire-pot section the said outer and inner concentric shells are connected integrally and are cored or drilled to provide a plurality of holes *b*, through which atmospheric air may pass, and these holes *b* are located in the fire-pot, preferably below the upper level of the body of coals and so that the air thus introduced at various places may mingle imme-

dately with the heavy gases freed by the burning coals, and thus insure the more perfect consumption of said gases than is possible when only a limited supply of air is passed upward between the grate-bars. Preferably the holes *b* are staggered or otherwise arranged out of annular alinement with each other, as shown, so that air may be introduced into the fire-pot at different levels and a more perfect distribution and commingling of said air with the gases will result than if said holes were all in the same plane.

Within the fire-pot and immediately over each hole *b* is a shield *c*, that is cast upon the inner shell of said fire-pot and extends sufficiently below the hole *b* to protect the latter against the entrance of ashes and particles of coals that would clog the said holes. Said shields thus provide protected chambers coincident with the holes into which chambers the fresh supply of oxygen is first discharged and then mingled with the adjacent gases. Around the circumferential wall of the fire-pot is a loosely-mounted ring-plate *d*, that is supported, as here shown, on brackets *d'*. This ring is vertically movable, being loosely supported on the said brackets, and thus capable of vertical adjustment to vary the amount of air admitted through the openings. The ring-plate *d* is provided with holes *d''*, that register with the holes *b* when my improvement is in service; but whenever it is desirable or necessary to cut off entirely or partially the air supplied through the holes *b* the plate *d* may be moved around, so as to carry the holes *d''* out of register with the holes *b*. In some instances I also provide a supplemental annular row of holes *e* around the upper part of the combustion-chamber or between the superimposed boiler-sections *e'*, so that an abundant supply of fresh oxygen may be introduced at some point above the bed of coals, and thus insure the complete consumption of the gases that otherwise might pass off unconsumed. A perforated ring or partial ring *f* is also provided, whereby the supplemental holes *e* may be covered or exposed, the ring *f* being supported and operable substantially like the ring-plate *d*, which I have described more in detail.

The steam-generator here shown is provided with the usual feed-door *g*, also with a clean-out door *h* and a clinker-door *i*.

My described improvements may be readily 5 and cheaply applied to all or nearly all forms of furnaces, and I find by practical demonstration that the calorific results are remarkably increased.

Having thus set forth my invention, I 10 claim—

In a furnace, a fire-pot section having concentric walls with integral connecting portions with staggered openings therethrough below the normal level of the fuel in the fire-pot, 15 said fire-pot being formed exteriorly with a

plurality of brackets *a*² below said openings, shields cast integral with the inner wall of the fire-pot and extending inward inclinedly over said openings, and a ring-plate having openings and loosely mounted upon and embracing the fire-pot and supported upon said brackets and capable of vertical adjustment, all substantially as shown and described. 20

In testimony whereof I have signed my name to this specification in the presence of two sub- 25 scribing witnesses.

FRANK H. PATRICK.
